UNITED STATES PATENT OFFICE.

HENRY FLICK, OF JACKSON, MICHIGAN, ASSIGNOR TO HAYES WHEEL COMPANY, OF JACKSON, MICHIGAN.

BILLET HOLDER FOR SPOKE-MITERING MACHINES.

Application filed October 4, 1921. Serial No. 505,246.

To all whom it may concern:

Be it known that I, HENRY FLICK, a citizen of the United States, residing at the city and county of Jackson, State of Michigan, have invented certain new and useful Improvements in Billet Holders for Spoke-Mitering Machines, of which the following is a specification.

This invention relates to improvements in billet holders for spoke mitering machines.

The objects of the invention are:

First, to provide an improved automatic billet holder for a spoke mitering machine.

Second, to provide a billet holder which will automatically force the trued side, bottom and end of a billet to position to insure uniformity of dimensions of the billets being made.

Further objects, and objects relating to details and economies of construction and operation will definitely appear from the detailed description to follow.

The objects of the invention are accomplished by the devices and means described in the following specification. The invention is clearly defined and pointed out in the claims.

A structure which is a preferred embodiment of the invention is fully illustrated in the accompanying drawings, forming a part of this application, in which:

Fig. I is a perspective view of a spoke mitering machine with the improved automatic billet holder in position, a portion of the frame and gearing being broken away.

Fig. II is an enlarged detail plan view of the billet holder and associated parts on the work table of the machine.

Fig. III is an enlarged detail elevation view of the billet holder from the front of the machine and from the front of Fig. II.

Fig. IV is an enlarged detail sectional view on line —4—4 of Fig. II.

Fig. V is a detail view of a billet in the rough.

Fig. VI is a detail view of the billet after the spoke miter has been cut.

In the drawings similar reference characters refer to similar parts throughout the several views.

Considering the drawings, the spoke mitering machine illustrated in Fig. I is similar to that appearing in the patent to

Scherer, #1,263,127, dated April 16, 1918, 55 which patent is owned by the Hayes Wheel Company, to which reference is made for detailed description of the main parts.

Considering the numbered parts of the drawings by their numbers, 1 is the main frame of the machine. 2 is the reciprocating knife head carrying the beveled cutter knives 2'. This head is reciprocated by the pitman 3 on the wrist pin 4 on the face plate 5. The machine is driven from the pulley 6 through train of gears 7.

The billet support 8 is on the work table 10 and is provided with an upwardly projecting stop 9 at its inner end, these parts being carried on the adjustable work table 110 which is adjustable by hand screws 10'. A fixed jaw 11 is secured by cap screw 11' to slide 11''. The slide is adjustable by set screw 12 and the angle of the fixed jaw is controlled by the set screws 13, 14,—see 75 Fig. II.

A movable jaw 15 is secured by cap screw 15' exactly similar to the cap screw 11' to the slide 17 having projections 17', set screws 18, 18 being provided to adjust and 80 control the angle of the same.

A compression coiled spring 16 holds the movable jaw 15 yieldingly away from the fixed jaw.

A bent lever 19 is pivoted on bracket 20 at 85 the pivot 20', the downwardly projecting end 19' being disposed to act upon the slide 17. A pull rod 21 connects to the said bent lever and is connected to the arm 22 of the actuating rock shaft 23 disposed beneath 90 upon the base of the machine. When this rock shaft is operated it will force the movable jaw 15 into contact with the spoke billet 27.

Rock shaft 24 is pivoted in bearings 95 25, 25 and an upwardly projecting arm 26 is disposed to act upon the end of the billet 27 and force it against the stop 9. This rock shaft is actuated by the pull rod 28 acting on the rock shaft arm 30, a compression spring 30' being interposed so that the connection is yielding. The lower end of the pull rod 28 is connected to the arm 29 carried by the rock shaft 23,—see Fig. I. The rock shaft 23 has arm 35 to which the 100 automatic actuating means is connected. This comprises a cam 31 on the driving plate 5 acting upon the cam follower roller 105

33 carried by the bent lever 32, which is connected by rod 34 to the said rock shaft arm 35, a compensating spring 36 being interposed to accommodate inequalities in 5 the size of the billets.

Having thus described the invention, what is claimed as new and desired to secure by Letters Patent, is:

1. In a spoke mitering machine, the combination with a table and reciprocating mitering knives with driving disk, wrist pin and pitman therefor, of a spoke billet support with an upwardly projecting end stop at its inner end, a clamping finger to force the billet endwise against the end stop, a rock shaft carrying said finger with yielding connection means to actuate the same, a stationary jaw at one side of said support, a movable jaw to cooperate therewith, a bent lever with connections for operating said movable jaw timed to act after the operation of said clamping finger, an actuating rock shaft with connecting rods to the said parts, a cam on the driving disk of said knives, and a lever with a cam follower timed to be actuated by the said cam connected to operate to clamp the billet in place in advance of the cut of the knife, coacting as specified.
2. In a spoke mitering machine, the combination with a table and reciprocating mitering knives with driving disk, wrist pin and pitman therefor, of a spoke billet support with an upwardly projecting end stop at its inner end, a stationary jaw at one side of said support, a movable jaw to cooperate therewith, a bent lever with connections for operating said movable jaw, a cam on the driving disk of said knives, and a lever with a cam follower timed to be actuated by the said cam connected to operate to clamp the billet in place in advance of the cut of the knife, coacting as specified.
3. In a spoke mitering machine, the combination with a table and reciprocating mitering knives with driving disk, wrist pin and pitman therefor, of a spoke billet support, a stationary jaw at one side of said support, a movable jaw to cooperate therewith, a bent lever with connections for operating said movable jaw, a cam on the driving disk of said knives, and a lever with a cam follower timed to be actuated by the said cam connected to operate to

clamp the billet in place in advance of the 55 cut of the knife, coacting as specified.

4. In a spoke mitering machine, the combination with a table and reciprocating mitering knives with driving disk, wrist pin and pitman therefor, of a spoke billet 60 support, with an upwardly projecting end stop at its inner end, a clamping finger to force the billet endwise against the end stop, a rock shaft carrying said finger with yielding connection means to actuate the same, 65 a stationary jaw at one side of said support, a movable jaw to cooperate therewith, a bent lever with connections for operating said movable jaw timed to act after the operation of said clamping finger, an actuating 70 rock shaft with connecting rods to the said parts, and means connected to operate to clamp the billet in place in advance of the cut of the knife, coacting as specified.

5. In a spoke mitering machine, the combination with a table and reciprocating mitering knives with driving disk, wrist pin and pitman therefor, of a spoke billet support with an upwardly projecting end stop at its inner end, a clamping finger to 75 force the billet endwise against the end stop, a rock shaft carrying said finger with yielding connection means to actuate the same, a stationary jaw at one side of said support, a movable jaw to cooperate therewith, 80 a bent lever with connections for operating said movable jaw timed to act after the operation of said clamping finger, an actuating rock shaft with connecting rods to the said parts, and means connected to operate to 85 clamp the billet in place in advance of the cut of the knife, coacting as specified.

6. In a spoke mitering machine, the combination with a table and reciprocating mitering knives with driving disk, wrist pin 95 and pitman therefor, of a billet support with an upwardly projecting end stop at its inner end, a stationary jaw at one side of said support, a movable jaw to cooperate therewith, a bent lever with connections for operating said movable jaw, an actuating rock shaft with connecting rods to the said parts 100 to actuate the same and clamp the billet in place, coacting as specified.

In witness whereof, I have hereunto set 105 my hand and seal.

HENRY FLICK. [L.S.]
